UNITED STATES PATENT OFFICE.

WILLIAM TOWNSHEND, OF HINSDALE, MASSACHUSETTS.

IMPROVEMENT IN LOOMS.

Specification forming part of Letters Patent No. 2,603, dated March 1, 1853.

To all whom it may concern:

Be it known that I, WILLIAM TOWNSHEND, of Hinsdale, in the county of Berkshire and State of Massachusetts, have invented, made, and applied to use certain new and useful Improvements in the Construction of Looms for Weaving, whereby the harness and heddles are moved with greater certainty in all kinds of figured weaving, and with less machinery than heretofore employed; also, the picking motion for throwing the shuttle is simplified, the warp is allowed to be drawn off the yarn-beam with more certainty and regularity, and the take-up motion for the cloth is more effective, simple, and cheap; and, lastly, the selvages to the cloth are formed by a peculiar arrangement of levers to work the sheds of the warp; and I do hereby declare that the following is a full, clear, and exact description of the construction and operation of the same, reference being had to the annexed drawings, making part of this specification, wherein—

Figure 1 is a plan of the loom complete. Fig. 2 is a vertical section longitudinally through the center of the loom. Fig. 3 is a front elevation of the parts complete. Fig. 4 is an elevation on the left side. Fig. 5 is a cross-section, showing the harness and parts that work the same. Fig. 6 is a back elevation of the parts that give motion to the chain that sets the pattern. Fig. 7 shows the cam and parts that work the selvage-harness, and Fig. 8 is a detached plan of the comb-levers and balance-rods that work the harness and heddles.

The like marks of reference denote the same parts.

a is the main driving-shaft, which is to be rotated by competent power, and furnished with a stop-motion from an auxiliary shaft or other convenient means, by which the shaft *a* can be stopped, as usual, and, all the motions of the loom being taken from this shaft, the whole of the parts become quiescent on stopping this.

b is the frame of the loom, made in any convenient shape or form.

c c are cranks on the shaft *a*, receiving connecting rods or arms *c'* to the lay *d*, by which the lay is vibrated.

d' are the reels, and *d''* the uprights or

swords connecting the lay with the rock-shaft 1, supported in journals on the frame *b*, as usual.

e e are upright frames on the frame *b*, receiving by tenons through mortises the head-pieces *e'*, which receive the cords to the heddles.

2 2 are adjusting-screws passing through the head-pieces *e'*, and resting on lugs or projections on the frames *e*. It will be seen that by this means the cords or straps to the heddles can be tightened when loose, or slackened when tight, according as the weather or wear may operate on the cords, so as to keep them at the proper tension.

e'' are the heddles and frames, to receive and pass the warp. These are suspended by cords or straps 3, passing up over pulleys 4 and 5, and between the pulley 5 and the frame *e* the cords 3 are united, so as to form but one distinct cord or strap to each heddle, which cords or straps pass over pulleys 6 at the junction of the frames *e* and head-pieces *e'*.

11 are hooks on the backs of balance-rods 10, hereinafter described.

f is a cross-piece beneath the heddles, receiving by adjustable eyes the spindle of the pulleys 8.

7 are cords or straps attached to the under side of the frame of the heddle, in the middle, which cords pass under the pulleys 8, and also under pulleys 9, on the frame *b*, and are attached to eyes on the lower end of the balance-rods 10. It will now be evident that each heddle can be moved up or down by any power applied to its balance-rod, and also that the balance-rods, being of the proper weight, effectually balance the heddles, so that the parts work more evenly and smoothly. I would here remark that any number of heddles, with their cords and balance-rods, may be used, although there are but six shown herein, the number of these being varied according to the pattern required to be woven. The balance-rods 10 are formed double, or as a long slot, made by bending the upper end over and down near to the vertical parts, and through the slot thus formed is a pin, 12, forming a center, on which the rods can be swayed or moved in the direction toward the heddles at the same time that they can slide up and down. *g* are a series of knees or right-angle

levers, corresponding in number to the number of the balance-rods and heddles. These knees move on a center-pin, 13. *h* is a face or shell cam on the outer end of the shaft *a*, on the outer side of which is an inclined projection or cam-piece, *i*', which, just as the lay is coming up to strike the filling into the cloth, as seen in Fig. 4, takes a roller, 25, on a right-angle lever, 26, on a fulcrum, 27, around which is a spring, (see Fig. 6,) that keeps the roller to the face of the cam *h*. The angle of the lever 26 takes, by a pin in a hole, the vertical lever 28, to the upper end of which is a sliding catch, 29, with a projection on the lower edge, that takes pins in a plate or wheel, 30, on a shaft, 31, supported in journals *k*. The shaft 31 has two heads or flanges on it between and near the journals *k*, which flanges have indentations to receive and carry the chain *k*'. This chain, *k*', is formed of any number of links connecting shafts or rods, on which are rollers, which roll on the shaft 31 as the chain is taken up one notch each rotation of the shaft *a*. It will be seen from the form of the sliding catch 29 that one pin being within the hook on the under side, and the next pin in the rear setting against the under side of the slide 29, the momentum of the chain cannot carry it more than one link at a time, the slide blocking it and requiring to be withdrawn horizontally to take up another notch or pin. The rollers on the chain *k*' set under the knees *g*, and the pattern being set up in the chain, reference being had to the lead of the warp in the heddles and the other parts, so as to compose the pattern correctly in the chain, as will be understood by the workman, each successive link of the chain, by its rollers, lifts some of the knees, while others drop between the rollers, as seen in Fig. 4. The knees or right-angle levers *g*, turning partly on their center, press the tops of the balance-rods inward, which balance-rods 10, moving on the center-pin 12, are moved out from the loom at their lower end, and held in this position during the other movements of the loom until the chain is again moved another link, when those balance-rods that are not held away from the loom by the knees *g* are brought into a vertical position by the tension of the cords to the heddles, the corresponding knee *g* dropping between the rollers on the chain *k*'. The object of this movement to the lower ends of the balance-rods is next to be set forth.

On the inner face of the cam-wheel *h* is a groove, 15, of the shape shown in Fig. 4 by dotted lines, the groove being eccentric to the shaft *a*, so as to give a motion to a roller, *i*, and draw it toward or force it away from the shaft *a*. This roller *i* is on and communicates its motion to a lower and outer comb-lever, 16, on a fulcrum, 17, on the frame *b*.

i' is a connecting-link from the moving end of the comb-lever 16 to the vibrating lever 18 on a fulcrum, 19, on the frame *b*.

20 is a link connecting the other end of the

lever 18 to a second and inner comb-lever, 21, on a fulcrum, 22. By this means, as the lever 16 is raised by the roller *i*, the lever 21 is depressed, and vice versa. On the lever 16 are teeth 23, similar to the teeth of a comb, and on the lever 21 are similar teeth, 24, set opposite, so that when the levers 16 and 21 pass each other the points of these comb-teeth just clear each other. On the balance-rods are notches 14 and *x*, which are formed by filing away the sides of the rods, so as to leave a knife-edge shaped part that enters between the teeth of the combs. At the time the lay reaches its farthest point forward (see Fig. 4) the levers 16 and 21 stand parallel to each other, and the groove 15 in the cam *h*, being concentric at this point, allows the levers 16 and 21 to remain quiescent for a short period. At this time the cam *i*' coming into operation, the chain is made to take up another link. Now, if there was no roller on the chain to raise the knees *g*, the balance-rods 10 would all remain in the comb-teeth 24 of the lever 21, and by their notches *x* would be carried down, elevating the heddles; and, on the contrary, if the chain was formed as a roller, all across all the knees *g* would be elevated and the lower notches, 14, of the balance-rods would all be struck into the comb-teeth 23 on the lever 16 and be elevated, depressing the heddles; but the chain being made with rollers, so as to elevate some knees *g*, while others are not acted on, some of the balance-rods remain in the comb-teeth 24, while others are struck over and retained in the comb 23, one being carried down, the other being carried up, elevates or depresses the heddles forming the warp into the shed, through which the shuttle is propelled on the lay, arriving at its backward position. It will be seen by reference to the shape of the groove 15 in the cam *h* nearest the center that it is concentric. At this point the lay has nearly arrived at its farthest backward motion, and the roller *i* being in this part of the groove, the sheds are held open, without having any motion until the shuttle is thrown, when the lay coming up to lay the filling the levers 16 and 21 are again brought parallel, the chain changed to another link, the balance-rods placed in their proper combs, and the operation proceeds as before.

I would here remark that the chain *k*' can be of any desired length to contain the pattern, and by my arrangement the rollers of the chain setting onto the shaft 21 are supported, and the parts do not require to be as heavy as ordinarily used to give the requisite strength.

On the shaft 31 is a small wheel, *l*, with indentations or holes in its face, taking the tapering point on a spring, 32, which point, entering the holes, gives sufficient resistance to prevent the chain turning as the sliding catch 29 is drawn back to take another pin in the plate 30. The periphery of this plate or wheel *l* is flattened in three places, as at 33, Fig. 3, (there being six links of the chain contained

around the shaft 31; but these flattened places on the wheel 7 must be for every two links in the chain.)

l' is a right-angle crank on a center, 34, the upper and horizontal arm resting on the periphery of the wheel l', and the other arm being vertical. When the horizontal arm is raised by the wheel l, the lower end of the lever will be to the left, and when the horizontal arm by the next motion of the chain comes into the flat part 33 the lower end of the lever l' is to the right. This motion gives the shuttle the blow or propulsion from first one end of the lay and then the other by the means next described.

35 are adjustable boxes on the frame b, through which are slide-bolts or staples 36 and 37, the back parts of which are connected by a wire or string going across the loom from one to the other. The lower end of the lever l' is formed as a fork, and sets over the staple 36. A spring, 39, applied in any convenient part, tends to pull the staples 36 and 37 toward the right side of the machine, and by consequence the horizontal part of the lever l' onto the wheel l. By reference to Figs. 1 and 3 it will be seen that one vibration of the lay causes the point 37 to protrude on the right side, while the point 36 is drawn within the box 35, and at the next motion of the lay the point 36 is protruded and the point 37 retracted by the spring. The points of these bolts or staples give motion to the shuttle alternately from first one side and then the other by the lay in its motion carrying the fulcrum of a lever on each side of the swords past the points 36 and 37, which, alternately taking these levers, move them, giving motion to the shuttle. 40 is the lever on left-hand sword, with a cord or strap at its lower end passing over a pulley or roller, 41, to one end of the right-angle crank m, set on a fulcrum on the rock-shaft, the vertical part of which has a cord or strap to the picker-lever, to give the impulse to the shuttle in the box 42 on the lay.

43 is the fulcrum of the picker-lever on the rock-shaft, and 44 is the spring to return the parts to their proper place. The backward motion of the lay, causing the lever 40 to take the point 36 and moving its fulcrum farther back, turns the lever and pulls on the cord over the pulley 41, elevating the horizontal part of the crank m and pulling on the picker-lever n.

The parts on the right side of the loom are precisely similar and act alternately with those on the left side, every other motion of the lay, by the pin or bolt 37, taking the upper end of the lever 45, drawing on the cord or strap over the pulley 46, and by the right-angle crank m' and its cord or strap giving motion to the picker-lever n' and shuttle when in the box 47 on the lay. As before, the lever n' and other parts are returned to place by a spring, 49, the lever n' being attached by the fulcrum 48 to the rock-shaft.

On one end of the shaft a is a double-grooved shell-cam, o, formed as shown in Fig. 7, and within this groove is a block made tapering at the ends, set on a stud, o¹, in a lever, o'. This lever o' is on a fulcrum, 50. The shape of the groove in the cam o is such that the piece traveling in the outer groove is raised up on one end by a projection opposite to the opening between the inner and outer groove, and enters the inner groove, and on the cam making another rotation a projection on the inner groove moves one end of the block downward, so that it enters the outer groove, so that by one rotation of the shaft a the lever o' is raised, and by the next rotation it is depressed. To the moving end of this lever o' is a link, 51, connecting to one end of a lever, o², running crosswise of the loom and set on a fulcrum, 52.

o² is a lever on a fulcrum, 54, on the center bar or cross-piece, f. The levers o² and o³ are connected by a pin passing through holes in the lever o² into a slot in the lever o³, by which means the lever o³ is given greater or less motion as the pin is either changed to a hole farther away from the fulcrum 52 or brought nearer to it.

55 are cords or straps from each end of the lever o³, passing up over pulleys 57 and down beneath pulleys or rollers 56. These cords or straps carry loops or heddles to receive and move the warp to form the selvage, and by the adjustable means for moving the lever o³ the warp for the selvage can be made to correspond with the sheds of the warp worked by the other heddles and harness.

A is the yarn-beam, from which the yarn passes over the warp-roller p through the heddles and reeds, as usual, the cloth being wound on the cloth-beam B.

p' is a friction-bar set against the warp on the yarn-beam, and kept to its place by two or more right-angle levers, q, on fulcrums 58, with adjustable weights 59. The operation of this part is that the bar p', being of the section shown and supported at the back, will have a certain amount of easing and working motion against the levers q, and the amount of friction on the warp as it unwinds will be regulated by the position of the weights 59. For instance, if the cloth is required to be thin, by placing the weights nearer the fulcrum 58 a given power employed to lay the filling will pull the warp along from under the bar p' sufficient for that width and closeness of filling, and if it is wanted to have a greater number of picks to the inch of cloth, by putting the weights out farther on the levers q more power will be required to pull the warp along, and consequently the filling will be driven so much closer, and as the yarn decreases in size the bar p' does not have so much bearing on the yarn, which allows for the decrease of size and consequent power of the warp to overcome the friction of the beam in its bearings, and the one balances the other. Thus, by this simple contrivance the warp is given off with regu-

larity and exactness until the whole of the yarn is used from off of the beam.

The cloth-beam B is provided with ratchets and clicks 64, or similar means to retain the amount of cloth taken up, which is effected by the following means:

60 are rods coming down from the breast-beam r to near the cloth-beam on each side of where the cloth is rolled.

s is a rod or strip of wood or similar material in front of the rods 60, in which are staples or pins 61, extending back toward the leg.

62 is an apron, of the width of the cloth, or may be straps or bands of cloth or similar material, as seen in Fig. 3, connecting the rod s with a weighted rod or bar, 63, of the proper weight, which tends to pull the rod s against the rods 60. The lay now coming up, takes the pins 61, shoving the rod or strip s toward the front of the loom, and, lifting the weight 63, and the apron 62 hugging the cloth, rotates it until the tension of the warp is as great as the friction of the apron, after which point the apron 62 and rod s slide on the cloth. The ratchets holding the cloth-beam, the weight 63 pulls the apron 62 down against as the lay recedes. It will thus be seen that the tightness of the cloth and warp is dependent solely on the amount of weight attached to the lower end of the apron or straps 62, for the more weight the more friction the cloth straps or apron 62 will have on the cloth to wind it up, the motion of the lay always giving sufficient motion to take up the cloth, and the apron sliding over the cloth when the warp is brought to the right tension by the regulated friction, and if no filling is deposited the cloth will not be eased by the lay to be taken up.

Instead of the staples 61, the lay-sword d' may have projections to take the rod s to move the same.

It will thus be seen that the loom works as a whole to produce cloth of the desired quality, although many of the parts may be used with looms of other construction. Therefore I do not mean to limit myself to their combined use.

I am not aware of any motion having been taken from the chain as herein shown, so that as each link of the chain is moved a bolt or staple is made to give the picking motion alternately on one side and then on the other,

and throw the shuttle by the motion of the lay. Neither am I aware of any similar arrangements of levers on the sides of the swords to move the picking-levers through the cranks, as herein shown, thereby dispensing with the cam, shaft, treadles, cog-wheels, bores, &c., now used.

I am aware that the cam o has been used to work the selvages; but I am not aware of any arrangement of levers having been made to give greater or less motion from the cam to the warp at the selvages, as herein set forth; and, lastly, I do not know of any take-up motion having been produced by the friction of an apron or straps taking the cloth, said straps or apron being given an intermittent motion from the lay and kept onto the cloth by the requisite weight.

I do not claim actuating the pickers by the backward motion of the lay alone; but

What I desire to secure by Letters Patent is—

1. The cam-wheel l on the chain-shaft 31, right-angle lever l', and staples or slide-bolts 36 and 37, combined and acting, as described and shown, to bring the picking motion into operation alternately on each side by the backward motion of the lay, as specified.

2. Actuating the picker-shafts by the lay on its backward motion by means of the vibrating studs when combined with levers 40 and 45, attached to the swords of the lay, and the bent levers m and m', the whole arranged and combined in the manner described.

3. The levers o² and o³, connected together by the adjustable pin, so as to give greater or less motion to the selvage-warp when actuated by the cam o, as described and shown.

4. The apron or straps 62, connected to the bar s and kept to the cloth by the proper weight or power, so as to cause sufficient friction to wind the cloth on the cloth-beam when said apron and bar are moved or actuated from the lay or otherwise, so as to produce the effects herein described and shown.

In testimony whereof I have hereunto set my signature this 21st day of August, 1852.

WM. TOWNSHEND.
